CUTTING BOARD

Donald W. Doman, Janesville, and Gerald A. Rau, Baraboo, Wis., assignors to Flambeau Products Corporation

Filed Apr. 1, 1974, Ser. No. 456,951

Term of patent 14 years

Int. Cl. D7—99

U.S. Cl. D7—46

FIG. 1 is a top plan view of a cutting board showing our new design;

FIG. 2 is a bottom view thereof;

FIG. 3 is one side thereof, the other side view being substantially identical;

FIG. 4 is one end view thereof;

FIG. 5 is the other end view thereof; and

FIG. 6 is a cross-sectional view taken along the line 6—6 in FIG. 1.

We claim:

The ornamental design of a cutting board, as shown and described.
